UNITED STATES PATENT OFFICE.

REINHOLD E. HENNINGES, OF CLEVELAND, OHIO.

WINDOW-SASH FASTENER.

No. 880,214.

Specification of Letters Patent.

Patented Feb. 25, 1908.

Application filed December 4, 1907. Serial No. 405,031.

To all whom it may concern:

Be it known that I, REINHOLD E. HENNINGES, a citizen of the United States, and a resident of Cleveland, in the county of Cuyahoga and State of Ohio, have invented a certain new and useful Window-Sash Fastener, of which the following is a specification.

This invention relates to window sash fasteners.

10 The object of the invention is to produce a sash fastener which will permit a slight raising of the lower sash, or lowering of the upper sash, but will prevent a complete opening from outside the window.

15 The invention consists of the construction and combination of elements hereinafter described and claimed.

Figure 1 is a broken perspective view of the meeting rails of two sashes, with the improved fastener applied. Fig. 2 is a section of the meeting rails of two sashes, with fastener applied, and Fig. 3 is a sectional view of a modified form of fastener.

Let A indicate the top rail of the lower sash of a window, and B the bottom rail of the upper sash. These may be of any usual construction.

To the rail B inside the glass, I attach the anchor or plate G by screws or other holding devices. A ring D is connected to this anchor plate G.

A short chain E is connected to ring D, so that the chain cannot be removed without breakage, or the absolute detachment of parts. The chain cannot be removed by any common tool which may be passed through the space between glasses when the window is slightly raised.

To the lower rail A, I attach an arch plate H, by any suitable means. Plate H is usually a metal casting, integral with the arch I, which arch I may be of ornamental form.

At the inside of the upper part of arch I there is a hook K, over which hook any link of chain E may be hung. The hook K may have a knob or barb L at its end, and as said hook is behind the body of the arch, when an attempt is made to reach it through the window crack, it is practically impossible to detach the chain from the hook in this manner, while it may readily be detached from inside the window. The chain links will only pass over barb L when in proper position.

55 The chain should be as long as the desired

latitude of movement of the sashes, say a few inches. As any link of the chain may be applied to the hook, the limit of movement of the sashes may be much less than the length of the chain.

60

When it is desired to fully open the window, the chain E may be detached from hook K, when the sashes will be free to move.

In Fig. 3 the outer sash carries a bracket or arch W which may be similar to arch I or a little lower. The chain is secured at one end to eyelet D on cross-bar X of the bracket. On each end, the bracket carries a prong Y designed to keep the chain from slipping off the ends of the cross-bar when slack. The bracket I on the inner sash is provided with a screw M. After the proper link of the chain has been put over the hook the screw is set up as shown in the figure. This forms a positive fastening for the chain. The screw is inaccessible by any ordinary means without breaking the glass of the outer sash. When this screw fastening is used it is impossible to remove the chain by the use of a stick or other tool passed between the meeting bars of the sashes.

I claim:

1. The combination, with the meeting rails of a pair of sashes, of a chain secured to one sash, and an arch provided with a hook, and secured to the rail of the other sash, so that a link of the chain may be attached to said hook.

2. A window sash fastener consisting of an anchor ring attachable to one sash, a chain attached to said ring, and an arched piece attachable to the other sash, and having a hook to which one of the chain links may be attached.

3. A window sash fastener consisting of a chain and anchor attachable to one of the sashes, a hook attachable to the other sash, and means coöperating with the hook to retain the chain thereon.

4. A window sash fastener comprising a chain and anchor attached to one sash, a hook attached to the other sash and on which a link of the chain may be placed and a screw serving to close the hook over the chain link and inaccessible for removal after the parts are in operative position.

REINHOLD E. HENNINGES.
